HONING DEVICE

Herbert Corral, St. Alban, Helensburg, and Bertram A. Stevens, Clydebank, Scotland, assignors to The Singer Manufacturing Company, Elizabeth, N. J., a corporation of New Jersey

Application February 5, 1936, Serial No. 62,403
In Great Britain September 3, 1935

7 Claims. (Cl. 51—69)

This invention relates to a sharpening device and more particularly to a hand operated sharpening device which may be used to sharpen the underedge trimmer blades used with sewing machines for the purpose of trimming the edge of the lower of the superposed plies of material being sewed.

One of the objects of this invention is to provide a simple, inexpensive, manually operable device for quickly sharpening the cutting edge of an underedge trimmer blade, the device embodying several adjustments by means of which the path of movement of the sharpening member may be adjusted so as to cause said member to accurately and uniformly sharpen the cutting edge. A further object of the invention is to provide a sharpening member which is reciprocable through a guide mounted for universal movement, the guide permitting angular adjustment 15 of the sharpening member about an axis parallel to its length. A still further object of the invention is to provide a sharpening device for sharpening under-edge trimmer blades which may be successfully used by a person having no more 20 than ordinary common skill in the use of sharpening implements.

With the above and other objects in view, as will hereinafter appear, the invention comprises the devices, combinations, and arrangements of 25 parts hereinafter set forth and illustrated in the accompanying drawings of a preferred embodiment of the invention, from which the several features of the invention and the advantages attained thereby will be readily understood by those skilled in the art.

In the drawings:

Figure 1 is a top plan view of the blade-sharpening device, showing a blade held in the supporting clamp and the sharpening stone in its operating position.

Figure 2 is a vertical sectional view taken substantially through the center of the guide for the sharpening element.

Figure 3 is a central vertical section taken 45 through the device, the sharpening element and its holder being shown in elevation.

Figure 4 is a vertical cross-section taken substantially along the line 4—4, of Figure 1.

In the embodiment illustrated this device comprises a rectangularly shaped bed 10 formed with an upstanding centrally apertured boss 11. Fitted into the aperture in the boss is a sleeve 12 formed with a groove 13 which receives one end of an adjusting screw 14. The groove 13 is larger than the end of the screw 14 and this construc-

tion permits the sleeve 12 to be adjusted vertically.

Journaled for turning movement about a vertical axis in the sleeve 12 is a shouldered screw 15 threaded into the U-shaped bracket 16 and between the upstanding arms of the bracket there is pivotally mounted on the pivotal screws 17 and 18 a collar 19 which is adapted to be turned about its horizontal axis. The collar 19 encircles a guide member 20 having a groove 21 in its outer periphery and into which the ends of the screws 17 and 18 extend. The thumb-screw 18 is adapted to engage the walls of the groove 21 to prevent turning of the guide 20 relative to the collar 19. This construction permits the 15 guide to be rotated relative to the collar for the purpose of adjustment and provides means for locking the guide in any adjusted position.

The sharpening member comprises a rectangularly shaped rod 22 provided with a handle 23 and lugs 24 having bifurcated ends which extend over the ends of the triangularly shaped sharpening stone 25. The lugs 24 are removably fixed to the rod 22 by the screws 26 and pins 27.

The edge of the base opposite the boss 11 is formed with an upstanding portion 28 having a horizontally disposed groove 29 (Fig. 3) in its top which receives the clamp or holder for the trimmer-blade. The clamp is formed of two parallel flat metal bars 31, 32 (Fig. 4) held together at one end by the shouldered screw 33 and at the other end by a thumb-screw 34. The trimmer blade 35 is clamped between the ends of the bars nearest the thumb-screw 34 and is held in its correct position by the studs 36 carried by the bar 32. It is to be understood that the shouldered screw 33 has a loose fit with the bar 31 and therefore the clamping ends of the bars 31 and 32 are separated by the spring 37 when the thumb-screw 34 is loosened.

To position the blades at the correct angle relative to the guide for the sharpening member an upstanding post 38 is formed at one corner of the base 10 and mounted in the post are stops 39 and 40 (Fig. 1) which are adapted to be held 45 in their adjusted positions by the screws 41 and 42, respectively. These stops are used separately depending upon the shape of the blade which is to be sharpened.

To sharpen a blade it is first clamped in the 50 blade-holder by the thumb-screw 34 and the holder is placed in the groove 29 on top of the upstanding portion 28. The holder is then moved longitudinally of the groove 29 until the end of the blade 35 abuts the end of one of the adjust- 55

able stops 39 or 40. The sharpening member is then placed on the gauge rest 43 formed on the upstanding portion 28, the screw 18 is loosened and the sharpening member is turned about its longitudinal axis until the lower side of the stone 25 lies flat on the upper surface of the gauge rest 43. The screw 18 is then tightened in order to hold the sharpening device in its correct position. The screw 14 may be loosened and 10 the sleeve raised or lowered to adjust the guide to the desired height. The sharpening member is then swung to the position shown in Fig. 1 and reciprocated by means of the handle 23 which is grasped in the hand of the operator and moved 15 back and forth in a manner readily understood.

It will be observed that the support for the guide permits the sharpening member to be swung in both the horizontal and vertical planes, and is, in effect, a universal joint. It will also 20 be observed that three adjustments may be made; first, the guide carrier may be raised or lowered; second, the sharpening member may be adjusted about its horizontal axis and third, the position of the trimmer blade may be determined by the 25 adjustable stops 39 or 40. This construction enables the guide to be accurately adjusted to guide the sharpening stone 25 at the correct angle relative to the cutting edge of the trimmer blade, which is at the foot of the upstanding portion 35 30 of the blade 35, and provides means for uniformly sharpening the edge when used by operators having no particular skill in the use of sharpening implements.

From the foregoing description it will be obvious that the elements employed are susceptible 35 of material variations. The privilege is therefore reserved of resorting to all such legitimate changes therein as may be fairly embodied within the spirit and scope of the appended claims.

Having thus set forth the nature of our invention, what we claim as new and desire to secure by Letters Patent is:—

1. A sharpening device of the class described comprising, a base, a blade-holder carried by said base, a support on said base, a guide pivotally mounted on said support, a rod extending through said guide and carrying a sharpening stone, said guide and rod being shaped so as to prevent the rod and guide from turning relative to each other, means for adjustably supporting said guide in said support for movement about the longitudinal axis of said rod and clamping means for holding said guide in its adjusted position.

2. A sharpening device of the class described comprising, a base, a blade-holding clamp carried by said base, an adjustable stop carried by said base and against which the blade is adapted to abut to position the latter, a support pivotally mounted on said base for movement about horizontal and vertical axes, a guide-member, a rod carrying a sharpening stone and extending through an opening in said guide, said opening and rod being constructed to prevent turning and movement relative to each other, means for adjustably supporting said guide-member in said support for movement about the longitudinal axis of said rod, clamping means for holding said guide-member in its adjusted position, and a handle on said rod by which it may be moved back and forth through the opening in said guide.

3. A sharpening device of the class described

for movement about a vertical axis, a supporting element pivotally secured to said bracket for movement about a horizontal axis, a guide-member provided with an opening and means for adjustably supporting said guide-member in 5 said supporting element for movement about the longitudinal axis of said opening and relative to said supporting element.

4. A sharpening device of the class described comprising, a base formed with an upstanding portion at one edge thereof and having a groove in its top, a blade-holder in said groove, an adjustable stop carried by said bed and against which one end of a blade is adapted to abut, a U-shaped bracket mounted on said base for movement about a vertical axis, a supporting element pivotally secured to said bracket for movement about a horizontal axis, a guide-member formed with an opening, a sharpening stone carrying bar having one of its ends extending 20 through said opening, said bar and opening being shaped so as to prevent turning movement of the bar in said opening, means for adjustably supporting said guide member in said supporting element for movement about the longitudinal axis of said bar and a handle for moving said bar back and forth through the opening in said guide.

5. A sharpening device of the class described comprising, a base formed with an upstanding portion at one edge thereof and having a groove in its top, a blade-holder in said groove, an adjustable stop carried by said bed and against which one end of a blade is adapted to abut, a bracket mounted on said base for movement 30 about a vertical axis, a supporting element pivotally secured to said bracket for movement about a horizontal axis, a guide-member formed with an opening, a sharpening stone carrying bar having one of its ends extending through said opening, said bar and opening being shaped so as to prevent turning movement of the bar in said opening, means for adjustably supporting said guide member in said supporting element for movement about the longitudinal axis of said 35 bar and means for maintaining said guide member in its adjusted position.

6. A sharpening device of the class described comprising, a base, a blade-holder carried by said base, a U-shaped support pivotally mounted on said base, a collar pivotally secured between the arms of said U-shaped support, said collar being movable about a horizontal axis, a guide provided with an opening, a rod extending through the opening in said guide and carrying a sharpening stone and means for adjustably supporting said guide in said collar for movement relative to said collar and about the longitudinal axis of said rod.

7. A sharpening device of the class described comprising, a base, a blade-holder carried by said base, a support mounted on said base for movement about a vertical axis, means for adjustably supporting said support so that its position relative to the base may be varied, a guide, a rod extending through said guide, said rod and guide having interlocking engagement to prevent the rod from turning in said guide but permitting endwise reciprocation of the rod, means for adjustably supporting said guide in said support 60 for movement about the longitudinal axis of 65 70
